[57] CLAIM

The ornamental design for the track light, as shown and
described.

DESCRIPTION

FIG. 1 is a perspective view of the track light;
FIG. 2 is a top view of the track light;
FIG. 3 is a first side view of the track light;
FIG. 4 is a front view of the track light;
FIG. 5 is a second side view of the track light;
FIG. 6 is a rear view of the track light; and,
FIG. 7 is a bottom view of the track light.
The track is shown in broken lines in FIG. 1 for illustrative
purposes only and forms no part of the claimed
design.

FIG. 1
